DISPENSING UNIT FOR THERAPEUTIC AGENTS

Walter A. Winsten, Forest Hills, N. Y., assignor to
 Food Research Laboratories, Inc., Long Island
 City, N. Y., a corporation of New York

Application April 5, 1949, Serial No. 85,584

8 Claims. (Cl. 167—63)

1

This invention relates to dispensing units adapted for the administration of therapeutic agents; and in particular is directed to units for dispensing an hydrophilic ointment which comprises penicillin, or other therapeutic agents unstable in aqueous media.

It is well known, for example, that penicillin in the form of various salts, such as the potassium, sodium, or calcium salt is unstable in aqueous media.

Such penicillin salts also are not stable when embodied in various hydrophilic ointment bases even if they contain but little or no water. The chemical groups such as the alcohol group or the carboxyl group and the like which confer hydrophilic properties to an ointment also contribute to the instability of the penicillin salt. As a consequence of such properties, it is not possible to prepare stable hydrophilic penicillin ointments. It has been the practice, in view of such instability, to employ hydrophobic ointment bases in which either crystalline or amorphous salts of penicillin are suspended, since it has been found that crystalline penicillin salts embodied in a hydrophobic base are quite stable.

However, it is well known that hydrophilic ointments are to be preferred over hydrophobic ointments by reason of the fact that they release penicillin more rapidly and in greater concentrations to affected or diseased tissues. A further advantage resides in the fact that hydrophilic ointments may more readily be removed by flushing with water or saline when such removal is desired.

In using the therapeutically more desirable hydrophilic ointments, it is necessary to prepare them as needed and promptly to use them after preparation. For this reason it has not been practicable heretofore to distribute or store hydrophilic penicillin ointments on a commercial basis because of the necessity for continuous refrigeration which itself is not conducive to the stability of certain types of ointment bases.

Accordingly, it is one of the principal objects of this invention to provide a hydrophilic ointment base preparation comprising penicillin salts and/or other therapeutic agents which are unstable in the presence of water, the therapeutic agent being present in such form that its stability is preserved over an extended period of time.

In its fundamental aspects this invention provides a dispensing unit comprising a hydrophilic ointment and a therapeutic agent unstable in the presence of water, so disposed with respect to each other that they may be mixed by the

2

patient immediately prior to the application of the drug. The unit consists essentially of a dual container, the outer phase holding the hydrophilic ointment base and a separately disposed inner phase holding the relatively small amount of the therapeutic agent, the two phases being kept sealed and apart from each other.

The objects and advantages of this invention will be more fully understood from the following detailed description thereof taken in connection with the accompanying drawing wherein:

Fig. 1 is a top plan view of a dispensing unit showing a form of this invention.

Fig. 2 is a cross-sectional view of the dispensing unit illustrated in Fig. 1 and taken on the line 2—2 thereof.

In the drawings the numeral 10 designates a heat and pressure sealable envelope of a plastic film, as, for example, compounded from polyvinyl chloride, rubber, and plasticizers, or any other appropriate durable and flexible material. Set within the envelope 10 is a hydrophilic ointment base 14 the composition of which is herein-after described. Within the matrix of the ointment base 14 there is located a small rupturable casing, as for example a capsule 16 or the like. The capsule 16 is filled with a hydrophobic material, such as an oil, fat, or wax, as for example, sesame oil or other appropriate material 18. If desired, the oil 18 may be thickened or rendered more viscous by hydrogenation or by the addition thereto of metallic soaps. There is suspended in the oil any stable salt of penicillin, such as the crystalline sodium, potassium, or procaine salts, or the amorphous salts thereof, such as the calcium salt. The penicillin salt is thus suspended in the hydrophobic material contained within the inner small capsule.

It will be observed that such structure that houses the penicillin salt suspended in the oil or other appropriate material of hydrophobic nature provides a dispensing unit in which the penicillin is maintained in stable condition. When it is desired to apply the drug in the form of the ointment containing the same, the procedure is as follows: The physician, nurse, or patient, holds the unit between the fingers and exerts pressure on the flexible outer wall 12 until the wall of the contained casing or capsule 16 is ruptured. Upon such rupture the penicillin suspended in the oily vehicle is brought into direct contact with the hydrophilic ointment 14. The unit is then manipulated until the penicillin is thoroughly distributed throughout the hydrophilic ointment.

The ointment itself comprises as a main constituent a wetting agent which imparts hydrophilic properties thereto. This wetting agent also solubilizes or readily disperses the oil or the hydrophobic material used to maintain the penicillin suspended in stable condition in the internal casing 16. The manipulation of the durable, flexible, outer plastic membrane of the unit may easily be effected so that the penicillin is rapidly distributed throughout the matrix of the hydrophilic ointment and the penicillin ointment thus made ready for application.

It will be observed that this invention utilizes the known stability of penicillin when suspended in a hydrophobic medium; and taking advantage of such stability allows for the easy incorporation of the penicillin, so suspended, into a hydrophilic medium that also possesses the property of instantly dispersing the hydrophobic suspending agent, thus bringing about the intimate contact of the penicillin with the hydrophilic medium. If the latter contains a small amount of water, the penicillin will dissolve during manipulation of the unit.

I have found that a hydrophilic ointment base containing principally a dispersing agent such as Tween 20 (a polyoxylethylene derivative of sorbitan monolaurate) is effective in solubilizing or dispersing hydrophobic penicillin compounds.

In place of Tween 20 there can be used Tween 40 or Tween 60, which are respectively the mono-palmitate and monostearate analogues.

A typical formulation of the hydrophilic ointment may be made as follows:

8 grams of stearic acid and 25 grams of Tween 20 are heated so as to obtain a solution thereof. There are then added to such solution 6.5 ml. of water or buffer (0.2 M phosphate buffer, pH 6.0) with stirring. On cooling the ointment base sets. The stearic acid imparts body to the ointment. In place of the stearic acid Carbowax 4,000 (a polyethylene glycol of average molecular weight, 4,000) may be used. It is unnecessary to add water to the above formulation.

Other ointment bases similar in character to the above are effective for the process, so long as they contain a principal amount of a wetting agent which confers hydrophilic properties and also serves to solubilize or disperse the hydrophobic material used for suspending the penicillin salt. It has been found convenient to fill the plastic dispensing unit with an amount of the hydrophilic ointment base, and to use a sufficient amount of penicillin within the inner rupturable casing or capsule, to provide for one dose or application.

In its most general aspect, this invention comprises a structure whereby penicillin, or other drug unstable in aqueous media, is suspended in a hydrophobic medium, the suspension being mechanically separated, by a suitable rupturable membrane, from a hydrophilic ointment base. The unit of such physical structure that the aforesaid membrane may be conveniently ruptured by manipulating the outer wall of the unit so as to bring the hydrophobic suspension of the penicillin into intimate contact with hydrophilic base, the base being of a type which has the property of solubilizing or dispersing the hydrophobic suspending agent so as readily to provide for the incorporation of the penicillin in the main body of the hydrophilic ointment.

It will be apparent that modified forms of such units may be used, as for example, a collapsible outer metal tube partly filled with a suitable hy-

drophilic ointment within which is disposed a rupturable cartridge containing a suspension of penicillin in a hydrophobic agent.

Among the various therapeutic agents which are unstable in the presence of water and, accordingly, can be put up only in hydrophobic materials in order to insure the shelf life thereof are: penicillin, bacitracin, and penicillin amide. The antibiotic bacitracin, a peptide-like substance, is also unstable in water or in hydrophilic bases. However, it is stable so long as it is maintained in contact with hydrophobic media. The amide of penicillin is an antibiotic derivative of penicillin also unstable in water.

It will be understood that the foregoing description is but illustrative of the means of accomplishing this invention and accordingly the appended claims are to be construed as defining the invention within the full spirit and scope thereof.

I claim:

1. A dispensing unit adapted for the administration of a hydrophilic ointment embodying a drug unstable in aqueous media, comprising: an envelope; a hydrophilic ointment contained within said envelope; a rupturable casing disposed within the envelope, said rupturable casing containing a hydrophobic material having distributed therethrough a drug unstable in aqueous media whereby the manipulation of the envelope effectuates the rupture of the casing and brings about the distribution of the drug in the hydrophilic ointment.

2. A dispensing unit adapted for the administration of a hydrophilic ointment embodying a drug unstable in aqueous media, which comprises: a tough, flexible outer envelope; a hydrophilic ointment comprising a wetting agent, said ointment being contained within the envelope; a rupturable casing disposed within the outer envelope; said casing containing a hydrophobic material having distributed therethrough a drug unstable in aqueous media whereby the manipulation of the envelope effectuates the rupture of the casing and brings about the distribution of the drug in the hydrophilic ointment.

3. A dispensing unit adapted for the administration of a hydrophilic ointment embodying a drug unstable in aqueous media, which comprises: a durable flexible outer envelope; a hydrophilic ointment, said ointment being contained within the envelope; a rupturable casing disposed within the envelope; said casing containing a penicillin salt distributed in a hydrophobic medium whereby the manipulation of the outer envelope effectuates the rupture of the casing and brings about the distribution of the penicillin salt in the hydrophilic ointment.

4. A dispensing unit adapted for the administration of a hydrophilic ointment embodying a drug unstable in aqueous media, which comprises: a durable flexible outer envelope; a hydrophilic ointment comprising a wetting agent contained within the outer envelope; a rupturable casing containing a hydrophobic material having distributed therethrough a salt of penicillin, said casing being disposed within the outer envelope whereby manipulation of the envelope effectuates the rupture of the casing and brings about the distribution of the penicillin in hydrophilic ointment.

5. A dispensing unit adapted for the administration of a hydrophilic ointment embodying a drug unstable in aqueous media, which comprises: a durable flexible outer envelope; a hydrophilic

ointment, said ointment being contained within the envelope; a rupturable casing disposed within the envelope; said casing containing penicillin amide distributed in a hydrophobic medium whereby the manipulation of the outer envelope effectuates the rupture of the casing and brings about the distribution of the penicillin amide in the hydrophilic ointment.

6. A dispensing unit adapted for the administration of a hydrophilic ointment embodying a drug unstable in aqueous media, which comprises: a durable flexible outer envelope; a hydrophilic ointment comprising a wetting agent contained within the outer envelope; a rupturable casing containing a hydrophobic material having distributed therethrough penicillin amide, said casing being disposed within the outer envelope whereby manipulation of the envelope effectuates the rupture of the casing and brings about the distribution of the penicillin in hydrophilic ointment.

7. A dispensing unit adapted for the administration of a hydrophilic ointment embodying a drug unstable in aqueous media, which comprises: a durable flexible outer envelope; a hydrophilic ointment, said ointment being contained within the envelope; a rupturable casing disposed within the envelope; said casing containing bacitracin distributed in a hydrophobic medium whereby the manipulation of the outer envelope effectuates the rupture of the casing and brings about the distribution of the bacitracin in the hydrophilic ointment.

8. A dispensing unit adapted for the administration of a hydrophilic ointment embodying a drug unstable in aqueous media, which comprises: a durable flexible outer envelope; a hydrophilic ointment comprising a wetting agent contained within the outer envelope; a rupturable casing containing a hydrophobic material having distributed therethrough bacitracin, said casing being disposed within the outer envelope whereby manipulation of the envelope effectuates the rupture of the casing and brings about the distribution of the bacitracin in hydrophilic ointment.
